UNITED STATES PATENT OFFICE.

DAVID A. GALANTIERE, OF CHICAGO, ILLINOIS

BINDER.

1,047,929.

Specification of Letters Patent. Patented Dec. 24, 1912.

Application filed March 11, 1911. Serial No. 613,822.

To all whom it may concern:

Be it known that I, DAVID A. GALANTIERE, a citizen of the United States, and resident of Chicago, in the county of Cook and State 5 of Illinois, have invented certain new and useful Improvements in Binders; and I do hereby declare that the following description of my said invention, taken in connection with the accompanying sheet of drawings, forms a full, clear, and exact specification, which will enable others skilled in the art to which it appertains to make and use the same.

This invention has general reference to 15 binders; and it consists, essentially, in the novel and peculiar combination of parts and details of construction, as hereinafter first fully set forth and described, and then pointed out in the claims.

20 The object of this invention is the production of an efficient, serviceable, and convenient loose leaf binder in which the leaves are clamped in a book for ready removal, replacing or refilling with new leaves. To attain these objects, I construct this binder substantially as illustrated in the drawings already mentioned, in which—

Figure 1 is a perspective view of a pocket card case constructed in accord with my invention. Fig. 2 is a similar view, the card case being shown in opened condition, a portion only of the flap being shown. Fig. 3 is a longitudinal section, and Fig. 4 a sectional elevation on line $x-x$ of Fig. 3. Fig. 5 is a 35 sectional plan on line $y-y$ of Fig. 4, the inside lining of the bottom of the cover being partly removed to disclose underlying parts. Fig. 6 is a plan of the blank from which the leaf-holder is formed.

40 Like parts are designated by the same symbols and characters of reference in all the figures.

A, in the drawings denotes the bottom cover member of the book, card case or similar container, and B, the top cover thereof, these parts being either stiff or flexible, as desired. This bottom member A, in the case of a pocket card-case, is provided with a flap C, which in folded condition laps over the 45 cover, as shown in Fig. 1. To this bottom member A there is secured a leaf-holder D, which comprises a box-shaped body having an open side through which the leaves are introduced, said box-shaped card holder 50 having a top member 12, two end members 13, 13^a, a back 14, and three bottom parts 15,

15^a, 15^b, respectively, said box-shaped card holder being formed from a single piece of sheet metal shown in plan view in Fig. 6.

In each of the end members 13, 13^a, there is a vertically disposed slot hole 16, whereby engage lugs 17, formed on a substantially rectangular clamping plate E, which clamping plate is located in the box-shaped casing D, and sustained in elevated position 60 therein by a preferably half-elliptical spring F, said spring being preferably fastened in its center to the bottom piece 15^b, by suitable means 18, as illustrated in Fig. 4. This clamping plate E is wider than the top 65 member 12 of the leaf-holder D, so as to project beyond this top member for some distance, as illustrated in Figs. 2 and 3, and the spring F is located about midway of the width of this clamping plate E. By this 70 construction of the plate E it is possible to pass the cards or leaves H underneath the top member 12 by placing the card or cards to be inserted near the outer edge of the top member 12 and then depressing, the cards 75 and with them the clamping plate E, and then pushing the cards under said top member 12, thereby avoiding the necessity of depressing the clamping plate E at the projecting lugs 17.

Near the end of the cover bottom A there is located a stop G, by which the cards, leaves, &c., are held in proper position, said stop G being a strip of metal bent at right angles and cemented to the bottom A underneath the inside lining 19, of said book bottom.

The blank of the box-shaped retainer D includes a rectangular central portion forming the top member 12, back 14, and bottom 90 portion 15^b. This rectangular central portion has at its sides extensions which are tapered and form the ends 13, 13^a, and further members which form the underlying portions of the bottom of the box, there being at the corners of the portions 15^b, holes 20, and in the portions 15, 15^a, similar holes 21, hereinafter to be again referred to. This blank has in the end members 13, 13^a the slot holes 16 already mentioned, and it is formed up by first bending the back 15^b at right angles along the dotted line 24, and then again bending at right angles along the dotted line 25. Now the end members 13, 15^a, are bent at right angles along the dotted lines 22, and then again at right angles along the dotted lines 23, which will bring 100 105 110

the bottom members 15, 15^a underneath the bottom member 15^b, and the holes 20, 21, into register, rivets or other suitable means being placed in said holes to securely unite 5 the bottom members.

The lugs on the clamping plate E pass through the slot holes 23 and project from the ends 13, 13^a sufficiently to enable the clamping plate E being depressed so that 10 the cards or leaves H, can be pushed underneath the top plate 12, and removably held in the retainer by the clamping plate E assisted by the spring F.

The box shaped retainer is secured to the 15 book bottom by being cemented thereto, the inside lining 19 overlapping the bottom members of the retainer D, as shown in Fig. 3.

In operation the clamping plate E is depressed by pushing at the lugs 17, when the 20 cards, leaves, boards &c., H, can be placed in position underneath the top member 12 above the clamping plate E. To remove a card &c., it is only necessary to pull at the same, the remainder of the cards being prevented 25 from moving by the stop G.

It is obvious that the means for holding the cards or leaves in position can be employed in any card case, loose leaf book, sample card case and other analogous devices without change or modification, the box-shaped retainer with the clamping plate and spring being made in various sizes to accommodate different widths of books:

35 I have shown in the drawings a curved blade spring, but it is evident that other shapes of springs may be employed without departing from the scope of my invention.

Having thus fully described this invention, I claim as new and desire to secure to me by Letters Patent of the United States—

1. A card or leaf holder, comprising, a cover having bottom, back, and top members, and a flap constructed to overlie said 45 cover member, a box-shaped retainer including top, end, and one side member, said end members being vertically slotted, a clamping plate in said retainer, said clamping plate having lugs constructed to pass through said 50 slots and project from said ends, said clamping member being wider than the retainer top member to project beyond the inner edge thereof, and a spring underneath said clamping plate constructed to support said 55 clamping plate near its ends and approximately medially of its width.

2. A card or leaf holder, comprising, in combination, a cover having bottom, back, and top members, a box-shaped container secured to said bottom member, including 60 an upper, two end, and one side members said end members being vertically slotted, a clamping plate in said retainer said clamping plate having laterally projecting lugs constructed to engage said vertical slots to 65 retain said clamping plate in movable position in said retainer, said clamping plate being wider than the retainer-top member to project beyond the inner edge thereof, and a spring underneath said clamping plate to 70 support the same near its ends and approximately medially of its width, whereby a card or leaf may be inserted in the retainer by placing the same upon the projecting portion of said clamping plate and then depressing the card and clamping plate simultaneously and pushing the card underneath the retainer-top member.

3. A device of the class described, comprising a pocket formed of sheet metal bent 80 upon itself to form a top, a back, a bottom, and side walls, said side walls being extended forward of the top wall, and each of said side walls having a vertically disposed guideway, a plate movably mounted in said 85 pocket and having parts engaging said guideways, and a spring having a middle curved part bearing on the middle part of said bottom wall and having ends bearing against the under side of said plate adjacent to its side edges and adapted to urge 90 said plate toward said top wall.

4. A device of the class described, comprising a pocket including a top, a back, a bottom, and side walls, said side walls being 95 extended forward of the top wall, and each of said side walls having a vertically disposed guideway, a plate movably mounted in said pocket and having parts engaging said guideways, and a spring having a 100 middle curved part bearing on the middle part of said bottom wall and having ends bearing against the under side of said plate adjacent to its side edges and adapted to urge 105 said plate toward said top wall.

In testimony that I claim the foregoing as my invention, I have hereunto set my hand in the presence of two subscribing witnesses.

DAVID A. GALANTIERE.
